UNITED STATES PATENT OFFICE

117,633

DESIGN FOR AN INCINERATOR

Leo G. Haase, Hollywood, Calif.

Application July 29, 1939, Serial No. 86,329

Term of patent 14 years

To all whom it may concern:

Be it known that I, Leo G. Haase, a citizen of the United States and residing at Hollywood, in the county of Los Angeles and State of California, have invented a new, original, and ornamental Design for an Incinerator, of which the following is a specification, reference being had to the accompanying drawing, forming a part thereof.

In the accompanying drawing, Fig. 1 is a per-

spective view of the incinerator showing my new design; and

Fig. 2 is a top plan view thereof.

The other side and the rear of the incinerator are substantially like the side shown.

I claim:

The ornamental design for an incinerator, substantially as shown and described.

LEO G. HAASE.
